COMBINED VELOCIPEDe AND HOBBY HORSE OR SIMILAR ARTICLE

Frank Pinto, Fort Worth, Tex.

Application July 17, 1953, Serial No. 26,036

Term of patent 3½ years

(Cl. D34—15)

FIG. 1.

FIG. 2.

To all whom it may concern:

Be it known that I, Frank Pinto, a citizen of the United States of America, residing at Fort Worth, in the county of Tarrant and State of Texas, have invented a new, original, and ornamental Design for a Combined Velocipede and Hobby Horse or Similar Article, of which the following is a specification, reference being had to the accompanying drawing, forming part thereof.

Figure 1 is a perspective view of a combined velocipede and hobby horse or similar article, showing my new design; and

Figure 2 is a top plan view thereof.

The side not shown has substantially the same appearance as the side shown in Figure 1.

I claim:

The ornamental design for a combined velocipede and hobby horse or similar article, substantially as shown and described.
